UNITED STATES PATENT OFFICE.

PAUL P. PARKER, OF INDIANAPOLIS, INDIANA, ASSIGNOR TO PARKER TIRE & RUBBER COMPANY, OF INDIANAPOLIS, INDIANA, A CORPORATION.

DESIGN FOR AN AUTOMOBILE-TIRE.

54,955.

Specification for Design.

Patented Apr. 20, 1920.

Application filed December 20, 1919. Serial No. 346,393. Term of patent 14 years.

To all whom it may concern:

Be it known that I, PAUL P. PARKER, a citizen of the United States of America, residing in the city of Indianapolis, county of Marion, and State of Indiana, have invented a new, original, and ornamental Design for an Automobile-Tire, of which the following is a specification, reference being had to the accompanying drawings, forming a part thereof.

In the drawings, Figure 1 is a plan view of the automobile tire, showing my new design, Fig. 2 is a developed view thereof, and Fig. 3 is a sectional view.

I claim:—

The ornamental design for an automobile tire, as shown.

PAUL P. PARKER.
